[57] ABSTRACT

A foam-preventing device for automobile hydraulic power units, comprising an intermediate pressure chamber located between an oil tank of the unit and the outlet of a flow-rate control valve of the unit for by-passing excess oil to the oil tank. Excess oil is forced by this arrangement to flow through the intermediate chamber so as to avoid a sudden pressure change and foaming thereof.

DEVICE FOR PREVENTING FOAMING OF OIL**BACKGROUND OF THE INVENTION****1. Field of the Invention**

This invention relates to a device for preventing pressure oil from foaming in the by-pass passage of an automobile hydraulic power unit.

2. Description of the Prior Art

Modern automobiles are equipped with a hydraulic power unit for automatic operations, such as power steering, automatic gear changing, window wiper and/or automatic door operation. To providing pressurized oil to the hydraulic power unit, an oil pump, usually a vane pump, is driven by using part of the output from the automobile-driving engine. The revolving speed of the engine, e.g., an internal combustion engine, varies depending on the automobile speed, for instance, from 500 to 7,000 rpm (revolutions per minute). Since the discharge from the vane pump increases in proportion to its revolving speed, the amount of oil delivered from the vane pump to the hydraulic power unit varies in response to the variation of the automobile engine speed.

On the other hand, the load to the hydraulic power unit in terms of oil flow-rate to members being controlled thereby is substantially constant, for instance, at about 6 liters per minute. Such constant oil flow-rate must, of course, be ensured even when the revolving speed of the automobile-driving engine is at its minimum.

Thus, as the amount of discharge from the vane pump increases in response to the increased speed of the automobile-driving engine, the surplus pressure oil in excess of the aforesaid constant flow-rate must be released from oil system of the hydraulic power unit. To this end, the surplus oil is passed to an oil tank through a by-pass type flow-rate control valve, for ensuring the constant oil flow to the members being controlled, regardless of the revolving speed of the automobile-driving engine.

With a conventional hydraulic power unit, the excess pressure oil is released to the oil tank at one atmospheric pressure level (1 Kg/cm^2) directly from the elevated pressure level at the valve gap of the flow-rate control valve communicating with the discharge of the vane pump. Since the discharge pressure from the vane pump can be as high as 10 Kg/cm^2 to 80 Kg/cm^2 , sudden release of the excess oil from such a high pressure to the atmospheric pressure causes considerable foaming in the oil due to the expansion of air dissolved therein.

The foaming of the oil is accompanied with unpleasant noise, which is referred to as "relief noise". The relief noise is particularly annoying when the vane pump is driven at a high speed without having any load to the hydraulic power unit, because substantially the entire discharge from the vane pump is released through the narrow gap of the flow-rate control valve under such conditions. Besides, if foamed oil is drawn into the vane pump from the oil tank, it tends to disturb the lubrication of the pump and to cause cavitation which may lead to accelerated wearing of the pump.

Therefore, an object of the present invention is to obviate the aforesaid difficulties of the conventional hydraulic power units.

SUMMARY OF THE INVENTION

The inventor has found through experiments that foams of hydraulic power unit oil, which are produced at the time of releasing its excess pressure, can be removed almost completely by applying a pressure (gauge pressure) of not smaller than 0.5 Kg/cm^2 to the foamed oil.

Based on such finding, the present invention uses an intermediate pressure chamber between the outlet of an oil pump, supplying pressure oil to the hydraulic power unit, and an oil tank surrounding the oil pump, which chamber has an orifice communicating with the oil tank so as to release the discharge from the oil pump to the oil tank through the chamber.

As a result, the foaming of that portion of the discharge, which is to be released or by-passed through a flow-rate control valve, is completely eliminated by reducing the pressure of the by-pass oil in two steps, i.e., to the pressure of the intermediate chamber and then to the atmospheric pressure, rather than directly to the atmospheric pressure in one step.

BRIEF DESCRIPTION OF THE DRAWING

For a better understanding of the invention, reference is made to the accompanying drawing, in which:

FIG. 1 is a sectional view of a hydraulic power unit for automobiles, according to the present invention;

FIG. 2 is a front view of the hydraulic power unit;

FIG. 3 is a partially cut away front view of the hydraulic power unit;

FIG. 4 is a sectional view taken along the line IV-IV of FIG. 3; and

FIG. 5 is a sectional view similar to FIG. 4, illustrating the open position of a flow-rate control valve.

Like parts are designated by like numerals throughout the different figures of the drawing.

DESCRIPTION OF THE PREFERRED EMBODIMENT

Referring to FIG. 1, a hydraulic power unit according to the present invention comprises a body 2 having projections 1 for facilitating the mounting of the unit to a stationary portion of automobile, e.g., the casing of an automobile-driving engine. A rotary shaft 3 extends through the body 2 in an oil-tight fashion, and a pulley 4 is secured to the outer end of the shaft 3, relative to the unit. An oil pump 5 is connected to the opposite end of the rotary shaft 3, so that driving power applied to the pulley 4 is transmitted to the oil pump 5 through the shaft 3. The oil pump 5 may be a vane pump, and in such a case, a rotor (not shown) of the vane pump is connected to the inner end of the rotary shaft 3. The pulley 4 may be driven by a part of the output from automobile-driving engine (not shown).

The oil pump 5 has an inlet port 6 and a discharge port 7. An oil-tight cover 8 encloses the oil pump 5 with a spacing therefrom. The cover 8 is secured to the body 2 while inserting an oil-tight packing 9 therebetween, as shown in FIG. 1. Thus, an oil tank 10 is formed by using the spacing between the oil pump 5 and the cover 8. The cover 8 has an oil inlet opening 11, which is normally closed by a lid 13. An oil strainer 12 is provided at the inlet 11 of the oil tank 10 for removing foreign matters from oil being supplied to the hydraulic power unit.

The oil pump 5 has a hollow boss 15 defining a passage 14 communicating with the outlet port 7 of the pump. The left-hand end of the boss 15, as seen in FIG. 1, engages the cover 8, and an annular oil-tight packing 16 is inserted between the edge surface of the boss 15 and the cover 8. The passage 14 of the boss 15 communicates with a corresponding hole passing through the cover 8, and a nipple 17 threadedly engages the left-hand end of the boss 15 for communicating the oil pump 5 to the load of the hydraulic power unit, while holding a mounting bracket 18 and the cover 8 between a flanged portion of the nipple 17 and the left-hand edge surface of the boss 15. An annular oil-tight packing 19 is placed between the outer peripheral surface of the nipple 17 and the inner wall surface of the passage 14 of the boss 15.

The nipple 17 has an orifice 17a formed at the end facing the outlet port 7 of the pump 5. Pressure oil delivered to the loads (not shown) of the hydraulic power unit through an orifice 17a returns to the oil tank 10 at a return path coupling 20 which is sealingly secured to the cover 8. The coupling 20 has a strainer 21 which is disposed within the oil tank 10.

Excess pressure oil at the outlet port 7 of the pump 5 is by-passed to the oil tank 10 through a flow-rate control valve 40, which includes a cylindrical valve hole 23 bored in the boss 15, so as to extend in parallel with the passage 14 thereof, as shown in FIGS. 3 to 5. The lower end of the passage 14, as seen in FIGS. 3 and 4, communicates with the corresponding lower end of the valve hole 23 through a port 22. The opening of the port 22 at the valve hole 23 is comparatively wide and extends nearly through a semi-circle about the longitudinal central axis of the valve hole 23. A piston valve 25 is slidably fitted in the cylindrical valve hole 23, so as to selectively communicate the port 22 with an annular groove 28 bored on the peripheral surface of the valve hole 23 with a short distance from the port 22, as shown in FIGS. 4 and 5. The piston valve 25 is biased by a coiled spring 24 in a direction to interrupt the communication between the port 22 and the annular groove 28. The piston valve 25 has a stopper 27 which limits the movement of the piston valve 25. Another annular oil-tight packing 26 is disposed between the boss 15 and the body 2, for preventing the leakage of the pressure oil through the boundary therebetween.

Another port 29 communicates the annular groove 28 on the peripheral surface of the valve hole 23 to an intermediate pressure chamber 30, which is a cylindrical hole bored through the boss 15 in parallel to the passage 14 and the valve hole 23, as shown in FIGS. 3 to 5. Thus, the lower end portion of the intermediate pressure chamber 30, as seen in FIGS. 4 and 5, has a bottom wall and communicates with the valve hole 23, while the upper portion of the chamber 30 communicates with the oil tank 10 through an orifice 30a formed at the wall of the intermediate pressure chamber 30 with a small distance from the open top of the chamber 30.

In the embodiment of FIGS. 4 and 5, a stay bolt 39 extends through the intermediate pressure chamber 30, so as to securely hold the cover 8 and the mounting bracket 18 against the open top of the chamber 30 for closing it. Such stay bolt 39 is not essential in the present invention, and it may be dispensed with if the open top of the chamber 30 is properly closed by the nipple 17 and associated fastening means.

The piston valve 25 has an axial hole 31, which extends coaxially with the longitudinal central axis of the piston valve 25 and has an open end at the back of the piston valve 25. Lateral holes 32 extend at right angles to the longitudinal axial center line of the piston valve, so as to communicate the axial hole 31 with the port 29 toward the chamber 30 at the lower end of the hole 31, as shown in FIGS. 4 and 5. After placing a valve holder 35 carrying a spherical valve 34 and a coiled spring 36 in the axial hole 31, a valve seat 33 is screwed in the open top end of the axial hole 31. The coiled spring 36 acts to normally urge the valve holder 35 upwards so as to keep a central passage of the valve seat 33 as blocked or closed by the spherical valve 34.

The upper portion of the valve hole 23 at the back of the piston valve 25 communicates with the passage of the nipple 17 at the downstream of the orifice 17a. Such communication between the valve hole 23 and the nipple 17 is provided by a passage 37 formed through the wall of the valve hole 23 and a radial hole 38 bored through the wall of the nipple 17, as shown in FIGS. 4 and 5.

In operation, the pressure difference between the line pressure at the downstream of the orifice 17a of the nipple 17 and the discharge pressure of the oil pump 5 at the discharge port 7 is applied across the piston valve 25. Thus, as the discharge from the oil pump 5 increases, the pressure acting on the lower surface of the piston valve 25 increases, so as to raise the valve 25 for widening the passage from the lower portion of the valve hole 23 to the annular groove 28, as shown in FIG. 5. As a result, the amount of by-pass oil toward the intermediate pressure chamber 30 increases. The oil delivered to the intermediate pressure chamber 30 is gradually released to the oil tank 10 through the orifice 30a. Accordingly, as the discharge pressure from the oil pump 5 is raised, the amount of the pressure oil discharged to the oil tank 10 increases, so as to keep the line pressure downstream of the orifice 17a substantially at a desired constant level.

It is apparent that, as the discharge from the oil pump 5 is decreased, the pressure acting on the lower surface of the piston valve 25 is reduced to allow the piston valve 25 to move downwards for restricting the amount of the pressure oil being by-passed from the oil pump discharge port 7 to the intermediate pressure chamber 30. Thus, the line pressure downstream of the orifice 17a is kept substantially at the desired constant level.

If the line pressure suddenly increases, due to one reason or other, the spherical valve 34 is pushed downwards for allowing the oil in the upper portion of the valve hole 23 to escape into the intermediate pressure chamber 30 through the central passage of the valve seat 33, the axial hole 31 of the piston valve 25, and the transverse holes 32 thereof. As a result, the pressure acting on the upper surface of the piston valve 25 is reduced to allow the piston valve 25 to move upwards for increasing the amount of by-pass oil for quickly reducing the line pressure.

The pressure of the discharge oil from the oil pump 5, as shown by the arrows α of FIGS. 4 and 5, can be as high as 10 Kg/cm² to 80 Kg/cm², depending on the operating conditions of the automobile. With conventional hydraulic power units, such high pressure of the discharge oil from the oil pump 5 is released directly to the oil tank 10 at the atmospheric pressure through a

narrow gap between the piston valve 25 and the annular groove 28. As a result, considerable foaming is caused in the oil of the oil tank 10, while generating annoying relief noise.

With the present invention, the oil being by-passed is not directly released to the oil tank 10, but it is once introduced to the lower portion of the intermediate pressure chamber 30, and then allowed to proceed into the oil tank 10 through the orifice 30a at the upper portion of the chamber 30. Thereby, the foaming of the oil and the relief noise are completely eliminated. The inventor has found that favorable results can be obtained when the differential pressure across the orifice 30a, i.e., between the intermediate pressure chamber 30 and the oil tank 10, is 0.5 Kg/cm² to 3 Kg/cm².

If the orifice 30a is too large, the differential pressure across it cannot be maintained in the aforesaid range, so that the desired function of the intermediate pressure chamber cannot be achieved. On the other hand, if the orifice 30a is too small, resistance to the by-pass flow of the oil becomes excessively high, and the desired flow-rate control characteristic and the desired constant line-pressure characteristic cannot be obtained.

As described in the foregoing disclosure, according to the present invention, there is provided a foam-preventing device to be used in a hydraulic power unit in cooperation with a by-pass type flow-rate control valve, for keeping a constant line pressure regardless of the revolving speed and discharge pressure of an oil pump. The foam-preventing device also eliminates relief noise by prohibiting the by-pass oil from foaming. Furthermore, the foam-preventing device of the present invention is effective in eliminating detrimental effects of foamed oil on the lubrication of an oil pump,

25
30
35

whereby a long service life of the oil pump can be ensured.

What is claimed is:

1. A device for preventing foaming of oil being bypassed in an automobile hydraulic power unit which latter includes a by-pass type flow-rate control valve which selectively by-passes part of the discharge from an oil pump into an oil tank so as to ensure desired oil flow toward loads of the unit, the device comprising an intermediate pressure chamber communicating with the outlet of said control valve through one port and having one orifice formed through a wall of said pressure chamber which faces said oil tank, whereby the entirety of the discharge part from said oil pump is guided to flow toward said oil tank through said orifice of the pressure chamber, the pressure of the discharge being regulated at a level between that at the discharge from said oil pump and that in said oil tank.
2. The device as defined in claim 1, wherein the differential pressure across said orifice of the pressure chamber is 0.5 to 3 Kg/cm².
3. The device as defined in claim 1, wherein said pressure chamber is an elongated cylindrical chamber disposed adjacent said control valve.
4. The device as defined in claim 3, wherein said pressure chamber receives the by-pass oil from said control valve at one longitudinal end thereof while delivering the by-pass oil to said oil tank at the opposite longitudinal end thereof.
5. The device as defined in claim 3, further comprising a stay bolt for said cylindrical pressure chamber, extending along the longitudinal center line thereof, for holding members close to at least one end of said chamber.
